US00D951271S

(12) **United States Design Patent** (10) Patent No.: **US D951,271 S**
(45) Date of Patent: **** May 10, 2022**

(54) **DISPLAY OR PORTION THEREOF WITH
GRAPHICAL USER INTERFACE**

(71) Applicant: **Apple Inc.**, Cupertino, CA (US)

(72) Inventors: **Patrick Lee Coffman**, San Francisco, CA (US); **Christopher P. Foss**, San Francisco, CA (US); **Andrew S. Kim**, Campbell, CA (US); **Jeffrey Dustin Tanner**, Walnut Creek, CA (US)

(73) Assignee: **Apple Inc.**, Cupertino, CA (US)

(**) Term: **15 Years**

(21) Appl. No.: **29/754,535**

(22) Filed: **Oct. 12, 2020**

(51) LOC (13) Cl. **14-04**

(52) U.S. Cl.

USPC **D14/485**

(58) Field of Classification Search

USPC D14/485-495

CPC G06F 3/048; G06F 3/0481

(57) **CLAIM**

The ornamental design for a display or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display or portion thereof with graphical user interface showing the claimed design.

The peripheral dashed broken lines depict a display or portion thereof, and form no part of the claimed design. The broken lines within the peripheral dashed broken lines depict portions of the graphical user interface which form no part of the display.
